DESIGN FOR A CHILD'S APRON

Justin I. Kingson, New York, N. Y., assignor to
George E. Mousley, Inc., New York, N. Y., a cor-
poration of New York

Application August 31, 1948, Serial No. 148,390

Term of patent 14 years

(Cl. D3—26)

To all whom it may concern:

Be it known that I, Justin I. Kingson, a citizen of the United States, residing at New York, in the county and State of New York, have invented a new, original, and ornamental Design for a Child's Apron, of which the following is a specification, reference being had to the accompanying drawing, forming a part thereof.

Figure 1 is a front view of the child's apron, embodying my new design and

Fig. 2 is a sectional view thereof taken on the line 2—2 of Fig. 1, and

Fig. 3 is a rear view thereof.

I claim:

The ornamental design for a child's apron, as shown.

JUSTIN I. KINGSON.
